CARBURETOR

Charles Horace Lionel Wynne, Ernest Walter Knott, and Andrew Craig Miller, Tyseley, Birmingham, England, assignors to Bendix Aviation Corporation, South Bend, Ind., a corporation of Delaware

Application April 6, 1933, Serial No. 664,694
In Great Britain June 4, 1932

3 Claims. (Cl. 261—41)

This invention relates to improvements in carburetors for internal combustion engines employing liquid fuel.

The object of our invention is to provide an improved carburetor having means for supplying to the engine when starting from cold a relatively rich and uniform mixture of fuel and air which is supplied independently of the mixture supplied from the main jet or jets and controlled by the throttle. Starting is effected with the throttle closed and the use of the auxiliary mixture-supplying means is, to a certain extent, equivalent to opening the throttle slightly and will keep the engine running faster than the normal idling speed, but the mixture supplied by the auxiliary means is richer than the mixture normally supplied by the carburetor with the throttle closed and is always uniform so that starting is greatly facilitated.

According to our invention a rotatable or otherwise movable valve member mounted in the carburetor body controls inter-communicating passages leading respectively to a jet or fuel well in the carburetor, to atmosphere, and to an opening or openings in the inlet manifold or in the main mixture supply tube on the engine side of the throttle. When starting the engine from cold the valve member is placed in such a position that all three passages are in communication with each other and the suction of the engine draws fuel from the jet or well, the fuel being broken up and mixed with air as it passes through the valve. The rate of feed of the fuel is conveniently controlled by a metering jet or restriction in the fuel passage on the supply side of the valve and the air inlet passage is so dimensioned as to give with the fuel the necessary rich mixture for starting, the total rate of supply of the mixture being preferably such as to permit the engine to turn over at a reasonably fast idling speed for warming up.

When the engine is sufficiently warm the valve is moved into a position to close the passages and fuel mixture is then drawn from the carburetor in the ordinary way by opening the throttle.

The valve member may be operated by hand from a control on the dash or other convenient point or it may be operated by a thermostat or by combined hand and thermostat controls. For example a thermostat may be arranged to prevent opening of the valve except when the engine is cold and to close the valve automatically when the engine is sufficiently warm.

The valve may also be interconnected with the

throttle in such a manner that the throttle can only be opened to a limited extent when the valve is open so that over-driving of the engine when cold will be prevented.

Two practical forms of our invention are illustrated by way of example in the accompanying drawing in which:

Figure 1 is a diagrammatic section of a form of our starting device applicable to any type of carburetor, the valve being shown in the closed position.

Figure 2 is a similar section showing the valve in the open position.

Figure 3 is a section showing a form of the device applicable to a carburetor of the type described in the specification of British patent application No. 22,002 of 1931.

Figure 4 is a diagrammatic showing of the carburetor illustrated in Figure 3.

In the construction illustrated in Figures 1 and 2 a is a cylindrical chamber formed in any convenient part of the carburetor body. Working through a gland nut b which closes the outer end of the chamber is a spindle c carrying a cylindrical piston d of any suitable material which is a good sliding fit in the cylinder. A passage e leads from one side of the cylinder to an opening f in the wall of the main mixture supply tube g on the engine side of the throttle valve h, and a passage j leads from the opposite side of the cylinder into a passage k. One end of this passage k opens to atmosphere through a calibrated orifice l and the other end of the passage leads into the float chamber m or other fuel reservoir, a restriction or jet n being located in the passage to control the rate of flow of the fuel.

For starting the engine the throttle valve is closed and the piston is moved into the position shown in Figure 2 in which the passages e and j are uncovered. The suction of the engine then draws fuel from the fuel reservoir m through the passages k and j and e and at the same time draws in through the orifice l air which mixes with and breaks up the fuel so that the fuel is delivered into the mixture supply tube in the form of a fine emulsion or rich mixture. The dimensions of the jet n and orifice l are so chosen as to give the necessary rich mixture for easy starting and to supply the mixture at such a rate as to permit the engine to turn over at a reasonably fast idling speed.

When the engine is sufficiently warm the piston valve is moved into the closed position as shown in Figure 1 and the throttle valve is opened to supply mixture to the engine in the ordinary way.

The piston valve may be operated in any convenient manner as for example by a cable or connected to a control on the dash or steering column.

In Figures 3 and 4 our invention is shown as applied to a carburetor of the type described in the specification of British patent application No. 22,002 of 1931, in which a fuel discharge device or jet is formed by an annular chamber 10 between an outer tube 12 to which fuel is fed from a constant-level supply chamber 13 and an inner tube *q* extending downwardly into the outer tube and open at its upper end to atmosphere, one or more apertures 14 being formed in the wall of the inner tube below the normal fuel level through which air can be drawn by the suction of the engine to mix with the fuel in the annular chamber 10.

In applying the present invention to a carburetor of that type the valve member consists of a cylindrical sleeve *p* rotatably mounted in the carburetor body in axial alignment with the inner tube *q*. An axial bore *r* extending through the valve sleeve receives at its inner end the upper end of the inner tube *q* which is suitably secured therein, and at the outer end of the valve sleeve which extends outside the carburetor body is a calibrated orifice *s* through which air is supplied to the inner tube during normal operation of the carburetor. The valve sleeve is also bored transversely as at *t* at right angles or at any convenient 30 inclination to the axial bore, and in the open or operative position of the valve one end of the transverse bore *t* is in alignment with a passage *u* leading to atmosphere and the other end is in alignment with a passage *v* leading either through 35 the wall of the main mixture tube or through an external tube to an opening on the engine side of the throttle 16.

Thus when the valve *p* is in its open position when the throttle is closed, the engine is in communication through the valve with the inner tube *q* which extends down into the fuel in the outer jet tube 12 and the engine draws fuel in from the inner tube *q* through the valve sleeve *p* and passage *v*. At the same time air is drawn in with the fuel from the passage *u* by means of the transverse bore *t* in the valve sleeve and mixes with the fuel as the fuel passes from the axial bore *r* into the transverse bore *t* so that the fuel is aerated and broken up.

50 The rate of feed of the fuel is conveniently controlled by a metering jet or restriction *w* in the axial bore *r* in the valve sleeve between the transverse bore and the upper end of the inner tube and the air supply may be controlled by a restriction *y* in the passage *u*.

When the engine is sufficiently warm the valve sleeve is rotated through a right angle so that the transverse bore *q* is cut off from the engine and from atmosphere but air can pass through the 60 axial bore *r* from the orifice *s* at its outer end to the inner tube to form an air-bleed for the fuel in the annular main jet 10.

To prevent over-driving of the engine when cold the valve sleeve *p* may be interconnected 65 with the throttle in such a way as to limit the

extent to which the throttle can be opened while the starting device is in use. In one convenient arrangement an arm on the valve sleeve *p* is connected by a slotted link to a lever keyed on the throttle spindle. The throttle control is connected to a second lever rotatably mounted on the throttle spindle and the two levers are connected by a tension spring and have engaging stops or lugs so arranged that when the valve sleeve is in the open or starting position the throttle can only be opened through, say, one fourth of its range although the spring connection between the levers permits the full normal movement of the accelerator pedal. When the engine has warmed up sufficiently the starting device is returned to its inoperative position by the hand control or thermostat and the throttle can then be opened to any desired extent, the spring connecting the two levers being sufficiently strong to carry the first lever and throttle spindle round with the second lever when the stop formed by the link from the starting device is disengaged.

We claim:

1. In a carburetor for an internal combustion engine, a main fuel nozzle comprising an inclined tube extending upwardly and inwardly into the carbureting passage and a tube of smaller cross section having one end projecting into said inclined tube and spaced therefrom to form a fuel discharge orifice, a conduit connecting the other end of the smaller tube to atmosphere, a manually operable valve controlling said conduit, and a second conduit connecting said smaller tube to the carburetor posterior to the throttle. 100

105 2. In a carburetor for an internal combustion engine, a main fuel nozzle comprising an inclined fuel tube extending upwardly and inwardly into the carbureting passage and an air bleed tube having one end projecting into said inclined tube and spaced therefrom to form a fuel discharge orifice, a conduit connecting the other end of the air bleed tube to atmosphere, a rotatable valve controlling said conduit, an orifice connecting said other end of the air bleed tube to 110 atmosphere independently of the first mentioned conduit, and a fuel conduit connecting said other end of the air bleed tube to the carburetor posterior to the throttle.

115 3. In a carburetor for an internal combustion engine, an inclined fuel tube extending upwardly and inwardly into the carbureting passage, a second tube having one end projecting into said inclined tube and spaced therefrom to form a fuel discharge orifice, a chamber at the other end of said second tube, a constantly open calibrated air inlet into said chamber, a second air inlet into said chamber, an outlet from the chamber to the carbureting passage posterior to the throttle, and a rotary valve manually operable 120 to simultaneously close said second air inlet and said outlet. 130
